CLAIM

I claim the ornamental design for an outer face of a vehicle wheel, as shown and described.

DESCRIPTION

FIG. 1 is a front view of an outer face of a vehicle wheel; FIG. 2 is a perspective view of the outer face of the vehicle wheel shown in FIG. 1; and,

FIG. 3 is a perspective view of the outer face of the vehicle wheel shown in FIG. 1.

Where included, broken lines showing environment or structure are for illustrative purposes only and form no part of the claimed design.

FIG. 3 is shown on a reduced scale as compared to FIG. 1.
